UNITED STATES PATENT OFFICE.

HENRY C. BUCHWALD, OF BALTIMORE, MARYLAND.

SLUG-CASTING MACHINE.

1,372,932.

Specification of Letters Patent. Patented Mar. 29, 1921.

Application filed November 10, 1920. Serial No. 423,025.

To all whom it may concern:

Be it known that I, HENRY C. BUCHWALD, a citizen of the United States, residing at Baltimore, in the State of Maryland, have 5 invented certain new and useful Improvements in Slug-Casting Machines; and I do hereby declare the following to be a full, clear, and exact description of the invention, such as will enable others skilled in the art 10 to which it appertains to make and use the same.

My invention relates to means for adjusting the slug space of a line casting mold in connection with machines of the Mergenthaler type, and consists primarily in means 15 whereby such space may be adjusted both as to length and thickness without disturbance of any of the stand and parts of the machine. The improvement is illustrated as 20 applied to a machine employing the ordinary mold carrier wheel such as is used in the Mergenthaler machine, though with slight modification it may be applied to machines employing other types of mold carrier 25 wheels.

In the drawings:

Figure 1 is an elevation of a portion of the mold carrier wheel with the mold cap adjusting means and liner inserting means 30 in operative relation with the mold thereof.

Fig. 2 is a section of the liner selecting arm 111 in Fig. 1 looking in the direction of the arrow 2.

Figs. 3 and 4 are diagrams illustrating 35 the various relations between the liners and liner inserting elements.

Fig. 5 is a sectional view through a typical mold carrier wheel showing the present improvements applied thereto, the section being 40 viewed in the direction of the arrow 5.

Fig. 6 is an enlarged detail view of one of the locking elements at the upper end of the mold cap 18 shown in Fig. 7 taken as 45 viewed in the direction of the arrow 6 in said figure.

Fig. 7 is a view similar to Fig. 1, but with the liner inserting means removed.

Fig. 8 is a front elevation of one form of flexible liner.

Fig. 9 is a view of the liner inserting means when viewed in the direction of the arrow 9 in Fig. 1, the mold carrier wheel 50 being omitted.

Fig. 10 is an enlarged detail view of the

mold cap distance regulating mechanism 55 taken as viewed in the direction of the arrow 10 in Fig. 7.

Fig. 11 is an enlarged perspective view of the lower portion of the fixed mold part 16 when viewed in the direction of the arrow 60 11 in Fig. 7.

Fig. 12 is a view of the liner selecting arm 111 with the bottom plate 112 thereof removed in order to show the feeler plates, viewed in the direction of the arrow 12 in 65 Fig. 5.

Fig. 13 is a perspective view of one of the feeler plates with the spring thereof attached.

Fig. 14 is a plan view of the bottom plate 70 112 of the liner selecting arm 111.

Fig. 15 is a view of a portion of the adjusting bar 102, shown at the upper part of Fig. 1, when viewed in the direction of the arrow 15 in said figure.

Fig. 16 is a view of the parts shown in Fig. 15 when viewed in the direction of the arrow 16 in said figure, and in addition to the parts there shown, an end view of the liner selecting arm 111 is also shown in one 80 of the positions it assumes during the operation of my improved slug casting machine.

In carrying out my invention I make use of any suitable slug trimming mechanism such as is illustrated in Patent No. 1,360,881, 85 Nov. 30, 1920. The slug trimming mechanism not being a part of the present invention will not be illustrated or described.

In the drawings:

The mold carrier wheel 14 is of typical 90 form and has the usual geared periphery 15 and fixed mold part 16. Within the usual cut-out portion 17 is arranged the adjustable mold cap 18 which in the present improvement carries the guide pins 49 and 20. 95 The cap 18 is held in adjusted positions by the spring-pressed pawls 21—21 which are articulated with the levers 22—22 and normally kept in the position shown in Fig. 7 by means of springs 23—23.

The levers 22 are each slidably and revolvably mounted at one end upon one of the screws 24—24 which are secured in the wheel 14. The other ends of the levers are pivoted together upon the screw 25 and the latter extends through a slot 26 provided in the wheel 14 and the end of said screw is threaded into the locking pin 27 which is 100 105

slidably mounted in a hole 28 provided in the wheel 14. The outer end of the pin 27 is beveled as shown in Figs. 5 and 7. Springs such as 29—29 pressing against 5 the levers 22—22 serve to normally keep them and the pin 27 in the positions shown in Figs. 5 and 7. The pin 27 is provided with a notch 30, and the detent 31, which is slidably mounted upon the wheel 14 in any 10 approved manner, is provided with a hole 32 through which the end of the pin 27 passes. The spring 33 mounted in a hole provided in the adjustable mold cap 18 pressing upwardly upon one end of the lever 15 34 which is pivotally mounted as at 35 upon the cap 18 serves to press the other end of the lever 34 downwardly and thus presses the edge of the hole 32 into the notch 30 and locks the pin 27 in its inward position. In its 20 inward position, the surfaces of the outer end of the pin 27 are substantially in alinement with the surfaces of the subjacent tooth 36. The ends of the pawls 21 are arranged to engage with a series of teeth 37—37 25 formed upon projections of the cap 18, as shown in Fig. 7.

Screws 38—38 are secured in the wheel 14 and they are provided on their inner ends with a series of buttress rings 39—39. The 30 beveled ends 40—40 of the slides 41—41 project into said rings and are normally kept therein by the pressure of springs, which are shown at 42 in Figs. 6 and 7.

There are two slides such as 41 in line 35 with each other for each of the series of buttress rings 39 and there is a spring such as 42 for each slide. This construction is adopted in order to provide for locking the cap 18 at each end upon two buttress rings.

40 The order to remove the beveled ends 40—40 from the buttress rings 39, the unlocking levers 43—43 are provided, each of which is pivoted upon a pin such as 44 secured in the mold cap 18. Each lever 45 43 has a depending arm 45 which normally rests against the upstanding arms 46—46 of the slides 41—41. The other end of each of the levers 43 is provided with a tappet face 47 which is substantially one-half the 50 thickness of the lever 43.

The plate 48 which is secured to the cap 18 by the screws shown in Fig. 7 overlies the portion of the lever 43 not covered by the tappet face 47 and prevents upward dis- 55 placement of the lever 43 from the position shown in Fig. 6.

The lower end, (as shown in Fig. 7), of the cap 18 is provided with an adjustable spacing mechanism constructed as fol- 60 lows:—

65 49 is a pin rigidly mounted in the lower end of the mold cap 18, the pinion 50 is revolvably mounted upon said pin and the pin 51 passing through the pin 49 prevents displacement of said pinion upon the pin 49.

Four cam plates are rigidly secured to the pinion 50 and revolve therewith. These cam plates have faces as at 56 which are substantially in alinement and the cam plate next to the pinion 50 is provided with a face 52, the next adjacent cam plate is provided with a face 53, the next adjacent cam plate is provided with a face 54 and the last cam plate is provided with a face 55. The cam faces 52, 53, 54 and 55 are located to co-act 75 with the index 57 as hereinafter explained.

The index 57 is inserted in a recess provided in the mold part 16 and projects into the hole 58 which is provided for clearance around the four cams. The hole 59 is provided in the mold part 16 for clearance around the pin 49. The index 57 is shown dotted in Fig. 10 in order to show its relation to the faces 52, 53, 54 and 55.

The pawls 21—21 not only lock the adjustable mold cap 18 but also serve to press said cap against the liners, such as shown in Fig. 8, and in addition, serve to press one of the cams having the faces 52, 53, 54 or 55 against the index 57.

90 The gear sector 60 is revolvably mounted upon the pin 61 and the latter is rigidly mounted in the mold cap 18. The gear sector 60 is provided with an arm 62 which is located opposite the slot 63 provided in the cap 18.

The spring 64 is revolvably mounted at one end upon the pin 65, the latter being rigidly secured in the mold cap 18 and the other end of said spring is secured within a hole 100 provided in the arm 62; the normal tendency of said spring being to keep the arm 62 in the position shown in Fig. 10, with the lowest tooth of the sector resting against the lower end of the spring 64, the latter 105 forming a stop for said sector.

A curved housing 66 is secured upon the wheel 14 and a curved slot 67 in the interior of said housing is in alinement with a similar curved slot in the wheel 14. The bottom of the slot in the wheel 14 is closed by the plate 68 which is secured to the wheel 14 by suitable screws.

A plurality of flexible liners, one of which is shown in Fig. 8, is slidably mounted in the 115 slot 67 and the corresponding slot in the wheel 14.

There are six liners mounted in the slot 67, the liner 69 nearest the mold part 16 being composed of four laminae and the other liners 70, 71, 72, 73 and 74 being each composed of two laminae. The laminae forming each liner are preferably soldered together at their ends so that the laminae may have mutual freedom to render them flexible, and the flexibility thereof is further increased by providing in each lamina a plurality of holes such as 75 and a slot 76. The laminae are parallelograms in profile and near one end, each lamina 130

is provided on one side with two projections 77 having opposing faces undercut as at 78, and between said faces, each lamina is provided with a point 79. In order to 5 guide the laminæ between the part 16 and the cap 18, the guide plate 80 is secured to the wheel 14 by the screw 81, and the screw 82 threaded into the wheel 14 bears against the outer end of the plate 80 and serves to 10 maintain the pressure of said plate against the laminæ.

In order to operate the locking pin 27, as 15 hereinafter described, the stop 83 is secured to any fixed part of the machine and the gear wheel 84 is revolubly mounted upon the pin 85 which is also secured to any fixed part of the machine.

In order to provide for the introduction of the proper number of liners between the 20 part 16 and the cap 18, for the introduction of said liners to the proper extent therebetween, for the operation of adjustable spacing mechanism and the locking mechanism hereinbefore described, the following 25 instrumentalities are provided:—

86 is a guide which is secured in any suitable manner to some fixed part of the machine and said guide is provided with a pair of gibs 87—87 upon which slides freely the 30 carrier block 88. The carrier block 88 is provided with suitable bearings 90—90 in which is revolubly mounted the shaft 89, the latter being formed integrally with the pinions 91—91. Springs 92—92 are mounted 35 upon the shaft 89, one end of each of said springs being secured in said shaft and the other end of said springs bearing against the carrier block 88. A ratchet wheel 93 is rigidly mounted upon the end of the shaft 40 89 between the prongs 94—94 formed in the end of the handle 95, the latter being provided with a spring pressed pawl 96 which engages with the teeth of the ratchet wheel 93. The pawl 96 may be removed from 45 engagement with the wheel 93 by pulling out the head 97 of the pawl 96.

The handle 95 is also provided with a spring pressed pawl 98 and the latter engages with the teeth of the ratchet sector 50 99 which is rigidly secured to the carrier block 88. The teeth of the ratchet wheel 93 are trenchant in a counter-clockwise direction as shown in Fig. 5 and the teeth of the ratchet sector 99 are trenchant in a 55 clockwise direction as shown in said figure.

The torsion of the springs 92—92 is such as to turn the shaft 89 in a counter-clockwise direction whenever the pawl 98 is removed from engagement with the teeth of 60 the ratchet sector 99. The carrier block 88 is provided with a dove-tailed groove 100 in which is slidably mounted the slide 101 formed integrally with the adjusting bar 102. The adjusting bar 102 is provided with 65 suitable bearings in which is revolubly

mounted a shaft 103 carrying at its upper end the hand wheel 104. The shaft 103 also carries the beveled gear 105 and the latter may be provided on its upper face with suitable indices which co-act with the 70 pointer 106 to indicate the extent of the introduction of the laminæ between the part 16 and the cap 18 as hereinafter explained.

The beveled gear 105 meshes with the bevel pinion 107 which is secured upon the 75 shaft 108, the latter being revolubly mounted in suitable bearings provided in the adjusting bar 102.

The shaft 108 is provided with a spiral groove 109 and the nut 110 slides freely 80 upon the shaft 108 and is provided with a spiral thread which fits in the groove 109.

The nut 110 is formed integrally with the liner selecting arm 111 and the latter is provided with the recesses 123 and 124, the 85 former being provided for the reception of the feeler plates 113, 114, 115, 116 and 117, and the recess 124 being provided for the reception of the feeler plates 118, 119, 120, 121 and 122, and said feeler plates are 90 retained within said recesses by the bottom plate 112. One of the feeler plates is shown in perspective in Fig. 13 and all of the feeler plates are similar in profile, each being provided with a finger 125 formed integrally with an arm 126 and on the end of the latter the spring 127 is clamped.

A groove 129 is provided in the adjusting bar 102 and above the center of said groove the spring 130 is secured to said bar. The 100 groove 129 is provided in order that the liner selecting arm 111 may be moved from the angular position with reference to the bar 102 shown in Fig. 5 to the angular position with reference to said bar shown in Fig. 16. 105

The bar 102 is provided with a rib 131 which extends the length thereof and is located to enter the groove 132 formed in the adjustable mold cap 18. The rib 131 is arranged to enter the groove 132 in order to 110 set the cap 18 and also, to operate the levers 34 and 43—43 as hereinafter explained.

The bar 102 is provided with an arm 133 which is located to strike the arm 62 of the gear sector 60, for a purpose hereinafter 115 explained.

A pin 134 is secured to the carrier block 88 and the link 135 is pivoted thereupon. The link 135 is articulated by means of the pin 136 with the lever 137 and the latter is secured to the shaft 138 which is formed integrally with the handle 139. The shaft 138 is revolubly mounted in bearings 140—140 secured to the guide 86.

The operation of my improved slug cast- 125 ing machine is as follows:—

If certain of the liners are between the part 16 and the cap 18 (as shown in Figs. 1 and 7), the handle 139 is to be moved to bring the appropriate feeler plates over said 130

liners, and the handle 95 is to be moved to bring said feeler plates into engagement with said liners, and also to introduce the rib 131 into the groove 132. The wheel 104 is then to be turned to move the liners 69, 70 and 71 backwardly so that their front ends will be in alinement with the front end of the liners 72, 73 and 74 (see Fig. 7.) The parts are then in position for a new setting and it is to be noted that when the rib 131 is introduced into the groove 132, as just explained, the arm 133 will come into engagement with the arm 62 of the gear sector 60 and will move the pinion 50 so that the cam plates having the faces 52, 53, 54 and 55 are rotated so as to be disengaged from the index 57. It is also to be noted that the rib 131 will come into contact with the lever 34 and will move said lever to remove the edge of the hole 32 from engagement with the notch 30 of the pin 27, thus allowing the springs 29—29 to move the pin 27 outwardly to the position shown in Fig. 7, thus removing the pawls 21—21 from the series of teeth 37—37 attached to the cap 18. The rib 131 also comes into contact with the faces 47—47 of the locking levers 43 and removes the beveled ends 40—40 of the slides 41—41 from the buttress rings 39—39 of the screws 38—38.

The handle 139 is then to be moved so as to move the cap 18 the proper distance from the part 16 so that the opening therebetween will be the proper width for the slug that is next to be cast.

While I have shown the handle 139 for moving the cap 18, it is to be understood that any suitable mechanism may be employed in lieu of the handle 139.

40 When my improved slug casting machine is used in connection with the Mergenthaler linotype machine, the mold cap 18 would be connected with the ordinary trimming knife of said machine so that it would move in unison therewith, as set forth in U. S. Letters Patent 1,360,881, Nov. 30, 1920.

When the mold cap 18 is set as just explained, the proper relation will be established between the approximate number of 50 feeler plates 113 to 122 inclusive and the corresponding liners 69 to 74 inclusive.

Referring to Fig. 3, it will be noted that there are two feeler plates 117 and 122 which are substantially equal in width to three of 55 the liners 72, 73 and 74, and that there are eight feeler plates 113 to 116 inclusive and 118 to 121 inclusive, each of which is substantially equal to the thickness of one of said liners. It is also to be noted that the 60 liner 69 is equal in width to two of the other liners; consequently, the total width of the liners 69 to 74 inclusive is equal to the total width of the feeler plates 113 to 117 inclusive and 118 to 122 inclusive.

65 If the cap has been set as just described

to mold a slug which is equal in width to the width of the liner 69, the relation of the parts is such that the right face of the feeler plates 117 and 122, (see Fig. 4), will be substantially in line with the right face of the 70 liner 69.

It is to be understood that when the handle 139 is moved as before explained, the wheel 104 is to be turned so that the arm 111 will be moved against the pressure of the 75 spring 130 from the position shown in Fig. 5 to the position shown in Fig. 16 in order to remove the feeler plates from the path of the liners while the mold cap 18 is being set.

After the mold cap has been set as just explained, it is evident that the fingers 125 of the feeler plates will enter into engagement with the faces 78—78 formed on the liners. The wheel 104 is then to be turned in order to move the arm 111 along the bar 102 and thus introduce the liner, (69 in the present instance), the proper distance between the part 16 and the cap 18. The distance said liner is introduced is indicated by the pointer 106 secured on the adjusting bar 102 and the indicia shown in Fig. 1 upon the bevel gear 105. The handle 95 is then to be moved to remove the feeler plates from engagement with the liners, the rib 131 from engagement with the sides of the groove 132 and the arm 133 from engagement with the arm 62 of the gear sector 60, and the handle 139 is then to be moved to withdraw the adjusting bar 102 and attached parts from the path of the mold carrier wheel 14 and its attached 95 parts. When the rib 131 is removed from the groove 132, as hereinbefore explained, said rib is removed from contact with the faces 47—47 of the levers 43—43 and, consequently, the springs 42 force the beveled ends 40—40 of the slides 41—41 into the buttress rings 39—39 and thus lock the cap 18 in position. At the same time, the rib 131 is removed from contact with the lever 34 and the spring 33 moves the detent 31 so 100 that the edge of the hole 32 is in proper relation to co-act with the notch 30 to lock the pin 27 as hereinafter explained.

When the arm 133 is removed from the arm 62, as hereinabove explained, the spring 115 64 revolves the pinion 50 and brings one of the faces 52, 53, 54 or 55 into engagement with the edge 140^a of the index 57 and, consequently, the adjacent portion of the cam plate next to the cam plate whose face 120 contacts with the edge 141 will overlie the index 57 on the face thereof next to the cap 18.

The cam plates having the faces 52 to 55 inclusive are to be made of such thicknesses 125 that when they overlie the front face of the index 57, as before explained, they will prevent the abutting face of the mold cap 18 (as shown in Fig. 7) from moving closer to the abutting face of the part 16 than the 130

thickness of the liner 69 and, consequently, parallelism of the slug space is assured.

When the adjusting bar 102 is moved to bring the right faces of the plates 117 and 122 (see Fig. 4) into alinement with the dotted line 141, then the feeler plates 117 and 122 will be in position to move the liners 69 and 70 and the appropriate face will make contact with the edge 140^a of the index 57 and the lower end of the abutting face of the cap 18, (see Fig. 7), will be prevented from moving closer to the abutting face of the part 16 than the sum of the widths of the liners 69 and 70 and, consequently, parallelism of the mold space is assured, as before explained.

The same effects obtain when the right faces of the feeler plates 122 are moved to alinement with the dotted lines 142, 143, 144 and 145 excepting that there will be a corresponding greater number of liners introduced within the mold space.

After the width of the mold space has been set, the appropriate number of liners introduced therein and the adjusting bar 102 moved backwardly, as just explained, the mold carrier wheel 140 is to be rotated in any approved manner, and during the rotation of said wheel, the locking pin 27 comes into engagement with the teeth of the gear 84 and said pin is moved toward the left from the position shown in Fig. 7 against the pressure of the springs 29-29. The movement of the locking pin 27 brings the teeth of the pawls 21-21 into engagement with the series of teeth 37-37 attached to the mold cap 18 and presses the inner face of said mold cap against the liners in the mold space and also presses the appropriate cam plate against the index 57, thus preventing the molten type metal from squirting between the liners and the abutting faces of the part 16 and cap 18.

When the pin 27 is pushed inwardly, as just explained, the edge of the hole 32 moves in to the notch 30 of said pin and thus the parts are locked in position.

During the continued motions and dwells of the carrier wheel 14, the slug is cast and trimmed and the carrier wheel returns to the positions shown in Figs. 1 and 7 and the cycle of operations may be repeated indefinitely with the same liners in the mold space.

When, however, it is desired to change the number of liners in the mold space or to vary the extent of their introduction therein, the adjusting bar 102 is to be moved, the liners in the mold space are to be moved and the cycle of adjustment hereinbefore explained is to be performed so as to introduce the desired number of liners between the mold space to the desired extent, and then at the beginning of the rotation of the mold carrier wheel 14, the mold cap 18 is

pressed against said liners and the further operation of the machine continued.

From the foregoing, it is evident that I have provided a simple and efficient means for varying the width and length of the mold casting space to any desired extent combined with the ability to quickly change the width and length as desired.

I claim:

1. A liner for use in slug casting, said liner comprising a plurality of laminae secured together at their ends.

2. A liner for use in slug casting, said liner comprising a plurality of laminae secured together at their ends and provided with perforations.

3. A liner for use in slug casting, said liner comprising a substantially parallelogrammic body provided with a pair of projections and a point therebetween.

4. In a slug casting machine, a mold having a fixed part and an adjustable part in combination with buttress rings and a slide having a beveled end to enter said rings.

5. In a slug casting machine, a mold having a fixed part and an adjustable part in combination with buttress rings, a slide having a beveled end to enter said rings and a spring for pressing said end into said rings.

6. In a slug casting machine, a mold having a fixed part and an adjustable part in combination with buttress rings, a slide having a beveled end to enter said rings, means for moving said end into engagement with said rings and means for withdrawing said end from said rings.

7. In a slug casting machine, a mold having a fixed part and an adjustable part in combination with buttress rings, a slide having a beveled end to enter said rings, a spring for pressing said end into said rings and means for withdrawing said end from said rings.

8. In a slug casting machine, a mold having a fixed part and an adjustable part in combination with buttress rings, a slide having a beveled end to enter said rings, a spring for pressing said end into said rings, a lever for removing said end from said rings and a bar for adjusting said adjustable part and operating said lever.

9. In a slug casting machine, a mold having a fixed part and an adjustable part in combination with buttress rings, a slide having a beveled end to enter said rings, a spring for pressing said end into said rings, a lever for removing said end from said rings, a groove in said adjustable part, an end of said lever extending into said groove, and a bar provided with a rib for entering said groove to adjust said adjustable part and operate said lever.

10. In a slug casting machine, a mold having a fixed part and an adjustable part

in combination with buttress rings, a slide having a beveled end to enter said rings, a spring for pressing said end into said rings, a lever for removing said end from said rings, a groove in said adjustable part, an end of said lever extending into said groove, a bar provided with a rib for entering said groove to operate said lever, and means for moving said rib into said groove to operate 10 said lever.

11. In a slug casting machine, a mold having a fixed part and an adjustable part in combination with buttress rings, a slide having a beveled end to enter said rings, a spring for pressing said end into said rings, a lever for removing said end from 15 said rings, a groove in said adjustable part, an end of said lever extending into said groove, a bar provided with a rib for entering said groove to operate said lever, means for moving said rib into said groove to operate said lever, and means for moving said rib to adjust said adjustable part.

12. In a slug casting machine, the combination with a mold carrier wheel, means for revolving said wheel, and fixed and adjustable mold parts mounted on said wheel, of means for adjusting said adjustable part while said wheel is at rest, and means for locking said adjustable part during the rotation of said wheel.

13. In a slug casting machine, the combination with a mold carrier wheel, and means for revolving said wheel, and fixed and adjustable mold parts mounted on said wheel, of means for adjusting and locking said adjustable part while said wheel is at rest, and additional means for locking said adjustable part during the rotation of said wheel.

14. In a slug casting machine, a mold having a fixed part and an adjustable part in combination with teeth on said adjustable part and a pawl for entering said teeth to lock said adjustable part.

15. In a slug casting machine, the combination with a mold carrier wheel, means for revolving said wheel, fixed and adjustable mold parts mounted on said wheel, and teeth on said adjustable part, of a pawl for entering said teeth and means for moving said pawl into said teeth during the revolution of said wheel.

16. In a slug casting machine, the combination with a mold carrier wheel, means for revolving said wheel, fixed and adjustable mold parts mounted on said wheel, and teeth on said adjustable part, of a pawl for entering said teeth, means for moving said pawl into said teeth during the revolution of said wheel and a spring for removing said pawl from said teeth.

17. In a slug casting machine, the combination with a mold carrier wheel, means for revolving said wheel, fixed and adjust-

able mold parts mounted on said wheel, and teeth on said adjustable part, of a pawl for entering said teeth, means for moving said pawl into said teeth during the revolution of said wheel, means for locking said pawl in engagement with said teeth and a spring for removing said pawl from said teeth.

18. In a slug casting machine, the combination with a mold carrier wheel, means for revolving said wheel, and fixed and adjustable mold parts mounted on said wheel, of liners between said mold parts, teeth on said adjustable part, and a pawl for entering said teeth to press said adjustable part against said liners.

19. In a slug casting machine, the combination with a mold carrier wheel, means for revolving said wheel, and fixed and adjustable mold parts mounted on said wheel, of liners between said mold parts, teeth on said adjustable part, and a pawl for entering said teeth to press said adjustable part against said liners and to lock said adjustable part.

20. In a slug casting machine, the combination with a mold carrier wheel, means for revolving said wheel, and fixed and adjustable mold parts mounted on said wheel, of liners between said mold parts, teeth on said adjustable part, a pawl for entering said teeth to press said adjustable part against said liners, and means for locking said pawl in position.

21. In a slug casting machine, the combination with a mold carrier wheel, means for revolving said wheel, and fixed and adjustable mold parts mounted on said wheel, of liners and adjustable spacing mechanism between said mold parts, teeth on said adjustable part, and a pawl for entering said teeth to press said adjustable part against said liners and mechanism.

22. In a slug casting machine, the combination with fixed and adjustable mold parts, of liners between said parts, means for moving said adjustable part against said liners and means for pressing said adjustable part against said liners.

23. In a slug casting machine, the combination with fixed and adjustable mold parts, of liners and adjustable spacing mechanism between said parts, means for moving said adjustable part against said liners and means for pressing said adjustable part against said liners and mechanism.

24. In a slug casting machine, the combination with fixed and adjustable mold parts, of liners between said parts, means for moving said adjustable part against said liners and means for pressing and locking said adjustable part against said liners.

25. In a slug casting machine, the combination with a mold carrier wheel and fixed and adjustable mold parts mounted on said wheel, means for revolving said wheel, of

liners between said parts, means for moving said adjustable part against said liners while said wheel is at rest, and means for pressing said adjustable part against said 5 liners during the revolution of said wheel.

26. In a slug casting machine, the combination with a mold carrier wheel and fixed and adjustable mold parts mounted on said wheel, means for revolving said wheel, of 10 liners between said parts, means for moving said adjustable part against said liners while said wheel is at rest, and means for pressing and locking said adjustable part against said liners during the revolution of 15 said wheel.

27. In a slug casting machine, the combination with fixed and adjustable mold parts, liners between said parts, a groove in said adjustable part, a bar, a rib on said 20 bar for entering said groove to move said adjustable part against said liners and means for moving said bar, of means for pressing said adjustable part against said liners, means for locking said pressing 25 means, and means for unlocking said pressing means operated by said rib.

28. In a slug casting machine, the combination with a mold carrier wheel provided with a toothed periphery, a gear meshing therewith and fixed and adjustable mold parts mounted on said wheel, of means for locking said adjustable part operated by 30 said gear.

29. In a slug casting machine, the combination with a mold carrier wheel provided with a toothed periphery, a gear meshing therewith and fixed and adjustable mold parts mounted on said wheel, of means for locking said adjustable part, including a locking pin extending beyond said 35 periphery and operated by said gear.

30. In a slug casting machine, the combination with a mold carrier wheel provided with a toothed periphery, a gear meshing therewith, a fixed stop adjacent to said gear, and fixed and adjustable mold parts mounted on said wheel, of means for locking said 45 adjustable part, including a locking pin extending beyond said periphery and limited 50 in outward movement by said stop and operated by said gear.

31. In a slug casting machine, fixed and adjustable mold parts in combination with a distance spacing mechanism comprising a 55 plurality of cam plates revolubly mounted on said adjustable part, an index on said fixed part and means for rotating said cam plates.

32. In a slug casting machine, fixed and 60 adjustable mold parts in combination with a distance spacing mechanism comprising a plurality of cam plates revolubly mounted on said adjustable part, an index on said

fixed part, means for rotating said cam plates, and means for pressing said cam 65 plates against said index.

33. In a slug casting machine, fixed and adjustable mold parts in combination with a distance spacing mechanism comprising a plurality of cam plates revolubly mounted 70 on said adjustable part, an index on said fixed part, means for rotating said cam plates, an adjusting bar for moving said adjustable part and an arm on said bar for operating said last-named means. 75

34. In a slug casting machine, the combination with a liner, of an arm for moving said liner, a nut formed on said arm, an adjusting bar, a spirally grooved shaft revolubly mounted in said bar and working in 80 said nut for moving said arm rectilinearly, and a groove in said bar permitting an angular movement of said arm to disengage it from said liner near the end of its rectilinear movement. 85

35. In a slug casting machine, the combination with a liner, of an arm for moving said liner, a nut formed on said arm, an adjusting bar, a spirally grooved shaft revolubly mounted in said bar and working in 90 said nut for moving said arm rectilinearly, a groove in said bar permitting an angular movement of said arm to disengage it from said liner near the end of its rectilinear movement, and a spring to restore said arm 95 to engagement with said liner.

36. In a slug casting machine, the combination with a guide, and a carrier block slidably mounted thereon, of an adjusting bar slidably mounted on said block, an adjustable mold part, means for moving said bar on said block to engage said bar with said part, and means for moving said block in said guide to adjust said part. 100

37. In a slug casting machine, the combination with a liner provided with a pair of projections, of a pair of feeler plates in line with said liner, each of said plates having a finger, one finger contacting with one projection to move the liner in one direction 105 and the other finger contacting with the other projection to move said liner in the opposite direction. 110

38. In a slug casting machine, the combination with a liner provided with a pair 115 of projections, of a pair of feeler plates in line with said liner, each of said plates having a finger, one finger contacting with one projection to move the liner in one direction and the other finger contacting with 120 the other projection to move said liner in the opposite direction, and springs for forcing said fingers into engagement with said projections.

In testimony whereof I affix my signature. 125
HENRY C. BUCHWALD.
